CLAIM

An ornamental design for a sealable housing for securely enclosing sensors, as shown and described.

DESCRIPTION

FIG. 1 is a front upper-left perspective view of an assembled sealable housing for securely enclosing sensors showing our new design;

FIG. 2 is a front lower-left perspective view thereof;

FIG. 3 is a front view thereof;

FIG. 4 is a left view thereof;

FIG. 5 is a right view thereof;

FIG. 6 is a top view thereof;

FIG. 7 is a bottom view thereof; and,

FIG. 8 is a rear upper-left perspective exploded view showing portions of the design not visible in the other views.

The broken lines show portions of the sealable housing that do not form part of the claimed design. The dash-dot lines define the bounds of the claimed design and form no part thereof.

As indicated herein, in implementations, the ornamental design as illustrated and claimed can be illustratively applied to a modular, waterproof housing for securely housing or enclosing one or more electronic, optical and/or other sensors and/or other components for measuring environmental data such as data related to temperature, light, moisture and/or other variables.
